CONVERTIBLE METALLIC COT

John H. Prescott, Columbus, Ohio

Application March 19, 1936, Serial No. 69,677

2 Claims. (Cl. 5-8)

This invention relates to a cot preferably adapted to be constructed of metal and to be convertible from a single form to a double form to support one or two springs and mattresses as required or preferred.

It is further aimed to provide a novel structure which is exceedingly simple, relatively inexpensive, durable and strong.

The more specific objects and advantages will become apparent from a consideration of the description following taken in connection with accompanying drawings illustrating an operative embodiment.

In said drawings:—

Figure 1 is a view in side elevation of the cot extended for double use;

Figure 2 is a side elevation of the cot folded for single use;

Figure 3 is an end elevation of the cot as required for double use;

Figure 4 is a substantially central vertical longitudinal sectional view through one end portion of the cot as folded for single use;

Figure 5 is a vertical sectional view taken on the line 5—5 of Figure 1;

Figure 6 is a vertical sectional view taken on the line 6—6 of Figure 1;

Figure 7 is a vertical sectional view taken on the line 7—7 of Figure 3;

Figure 8 is a vertical sectional view taken on the line 8—8 of Figure 7;

Figure 9 is a detailed sectional view taken on the line 9—9 of Figure 7;

Figure 10 is a detailed sectional view taken on the line 10—10 of Figure 8; and

Figure 11 is a detailed sectional view taken on the line 11—11 of Figure 1.

Referring specifically to the drawings wherein like reference characters designate like or similar parts, the device employs a lower spring and mattress supporting frame 10 and an upper spring and mattress supporting frame 11. Said frame 10 is made of suitable angle iron material, with the vertical flanges uppermost and the frame is rectangular. Such frame is elevated from the floor by means of floor legs 12 depending from the same adjacent the corners and which legs are preferably tubular so that casters may be mounted therein if desired.

The upper spring and mattress supporting frame 11 is rectangular and preferably of angle iron material having a vertical flange or wall 13 extending above and below a horizontal inwardly extending flange 14.

Pivotedly connected to the vertical flanges of the

frames 10 and 13 are links 15 preferably of angle iron material, the pivotal connections being on horizontal axis as at 16. A pair of such links are provided at each corner of the cot and the pairs are hinged or pivotally connected together on horizontal axis as at 17. It will be realized that the cot may assume the position of figure 1 wherein the frames 10 and 11 are vertically spaced so that each of them may support a spring and mattress. When a single spring and mattress are supported, links are swung downwardly and inwardly from the position of figure 1 to the position of figure 2 wherein the frame 11 is superposed and supported on the frame 10. In such instance, the frame 11 alone accommodates a spring and mattress.

The upper and lower links 15 at each end of the cot are suitably braced in the extended position as through the medium of cross chains 18, of metal connected to the links, as best shown in Figure 3.

Suitable means are provided whereby the links are braced and effectively held in the vertical position of Figure 1. To this end, brace rods 19 are employed. Such brace rods have angular end portions 20 passing through plates 21 preferably welded to the links 15. Beyond such plates, the brace rods 19 have heads 22 which are preferably accommodated in openings 23 in said links 15. The other ends of the rods 19 have lateral lugs 24 thereon which are engageable in opening 25 in the vertical flanges of the frame 10. The braces at 19 are somewhat resilient to enable them to be sprung so as to engage and disengage the openings 25.

In lieu of the said brace rods 19 or in addition thereto, if preferred, the links 15 adjacent the pivots 17 may have eyelets 26 thereon, through which a rod or bolt 27 may be removably passed, in order to prevent the breaking of the joints at the hinges.

It will be noted that one flange of the links 15 at an end thereof, directly contact with adjacent vertical flanges of the frames 10 and 13, to prevent unfolding of the links 15 past the vertical flanges.

Various changes may be resorted to provided they fall within the spirit and scope of the invention.

I claim as my invention:—

1. A cot of the class described having a lower 50 mattress supporting frame, an upper mattress supporting frame adapted to assume a superposed position on the lower mattress frame, said frames having vertical flanges, the upper mattress frame having a mattress-supporting flange ex- 55

tending inwardly below the top thereof, pairs of links at the corners of the cot, the links of each pair being pivoted together, said links being of angle form in cross section and each cutaway at 5 one flange thereof to provide extensions pivoted to the frames on the interior thereof, the ends of the cutaway flanges of each link in the unfolded condition of the cot resting on the edges of the vertical flange of the engaged adjacent frame, 10 and means operable to maintain the links against collapse in the unfolded condition.

2. A cot of the class described having a lower mattress supporting frame, an upper mattress supporting frame adapted to assume a superposed 15 position on the lower mattress frame, said frames having vertical flanges, the upper mattress frame

having a mattress-supporting flange extending inwardly below the top thereof, pairs of links at the corners of the cot, the links of each pair being pivoted together, said links being of angle form in cross section and each cutaway at one flange 5 thereof to provide extensions pivoted to the frames on the interior thereof, the ends of the cutaway flanges of each link in the unfolded condition of the cot resting on the edges of the vertical flange of the engaged adjacent frame, and 10 means operable to maintain the links against collapse in the unfolded condition, comprising brace rods pivoted to certain of the links and engageable with the lower frame, and means extending across the joints of the links of each pair. 15

JOHN H. PRESCOTT.
